UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

RADIOPHONE SYSTEM.

Application filed September 26, 1924, Serial No. 740,113. Renewed February 11, 1926.

To all whom it may concern:

Be it known that I, EDWARD E. CLEMENT, a citizen of the United States, residing at Washington, in the District of Columbia, have invented certain new and useful Improvements in Radiophone Systems, of which the following is a specification, reference being had therein to the accompanying drawing.

10 My invention relates to systems of communication, and particularly to telephone and radio systems. The present application is a continuation in part of my copending application, Serial No. 581,829, filed August 15 14, 1922, now Patent No. 1,522,357, dated Jan. 6, 1925, the present invention having for its main object the provision of centralized maintenance and control through the centralization of the source of power or energizing current for the service units. Another object is to provide a system of distribution for such centralized current supply which may be phantomed on the telephone wires without interfering with their 20 normal functions. A further object is to provide means for extending the centralized power supply system to sub-centers such as private branch exchange systems. Other 25 objects of my invention will be apparent from a perusal of the following specification and the drawings accompanying the same.

My invention is illustrated in the accompanying drawings, in which:

30 Fig. 1 is a diagram showing a general system embodying the same;

35 Fig. 2 is a diagram showing a central station telephone switchboard, subscribers' lines terminating thereon, and subscribers' 40 telephones connected thereto;

Fig. 2^a shows a modification of the system of Figs. 2 and 3;

45 Fig. 3 is a diagram to be read in connection with Fig. 2, showing the radiophone set at one of the subscribers' stations, and the radio switchboard and associated equipment at the central station.

50 Fig. 4 is a diagram showing a simplified arrangement for controlling and charging the battery of a substation radiophone set over a phantom circuit imposed on a magneto telephone circuit.

55 Fig. 5 is a schematic diagram of a private branch exchange system with radiophone receivers at the subscriber's station supplied

with energizing current from a common source secondary to a centralized source at the main exchange.

Fig. 6 is a more detailed circuit diagram of the system of Fig. 5. 60

Fig. 7 is a fragmentary circuit diagram of a modification of the charging system of Fig. 6.

Fig. 8 is a further modification of the charging system of Fig. 6 using a local generator. 65

Fig. 9 is a further modification of the system of Fig. 6 with local generation at the private branch exchange station taking power supply over the phantom circuit. 70

Referring to Fig. 1, 1, 2 and 3 represent telephone subscribers' stations connected by wires 4, 5 and 6 to the central telephone exchange 7, constituting the distributing center for the area in which local subscribers 75 1, 2, 3, etc., are located. Superposed upon this telephone system is a radiophone system comprising a central station 8 and subscribers' stations 1^a, 2^a, 3^a, etc. The central radio station or exchange is provided with switchboards and a complete broadcasting equipment, and the subscribers' stations 1^a, 2^a, 3^a, etc., are provided with receiving instruments all standardized for the same wave length, and adapted to respond to the waves radiated from the central station 8. The interrelation between the telephone system and the radiophone system is by means of physical connections indicated at 1^b, 2^b, and 3^b at the subscribers' stations, and multiples or 80 trunk extensions 15 from the telephone exchange switchboards to the radiophone exchange switchboard in station No. 8. The detail of these connections will appear hereinafter, but it should be stated here that the 85 system of connections is such that telephone wired traffic has the right of way over the wires, while the radio traffic has the right of way over the radio side of the system. The arrangement is such that the radio operator 90 cannot interfere with telephone operation, nor can a telephone operator interfere with the radio operation, although under proper conditions each can act freely by way of borrowing facilities from the other. At all 95 times, should a question of precedence arise, the apparatus is arranged so as automatically to cut off the radio connections and to leave the wired lines clear for telephonic use.

100 Stations 12, 13 and 14 in this figure are 110

typical of indifferently located distant stations which may or may not be a part of this particular system. As the figure is typical only, no attempt has been made to 5 give the geographical location of such stations or to show the actual arrangement and distribution of the telephone centers through which final broadcasting to the subscribers must take place. The main purpose of this 10 figure is to crystallize the method employed, by which the development of a very large number of unrelated individual receiving stations is replaced by an orderly system of distribution through the telephone centers, 15 whereby the individual receiving instruments are localized, maintained, controlled, and supplied with definite service through regular channels, for which a definite charge can be made and collected in the manner 20 usual in wired systems of communication. Inasmuch as the number of wave lengths available for transmission is limited in the present state of the art, advantage is taken of the organized system of wire distribution 25 and localization to create a phantom system controlled and guided thereby.

Briefly stated, as indicated in Fig. 1, each radio central station or radio department of a telephone exchange, is not only 30 provided with broadcasting equipment for its subscribers, but also with radio receivers adjustable by tuning to wave lengths allotted to such stations as those indicated at 12, 13 and 14, as well as primary stations 35 maintained and operated by or under the direction of the telephone organization itself. By means understood in the art, messages received at the radio central stations are relayed on their respective standard wave 40 lengths to the local subscribers.

Referring to Figs. 2 and 3, I have therein shown circuits of the central office and substation equipments and connections, Fig. 2 representing the telephone side of the system, and Fig. 3 the radiophone side of the 45 system. Before proceeding to detail description it may be noted that in accordance with standard telephone practice, provision is made for keeping the telephone lines and 50 central office circuits clear of all grounds or other disturbing connections during conversation. When the radiophone goes into service, by closing the filament switch its operation in receiving is identical with that 55 of any radio receiver, and in the event that use is made of any partial transmission of waves over the line wires, as will be herein-after pointed out, said waves will be at a frequency above or below the limits of audition. In the present diagram, I have shown 60 the circuits arranged with nothing but continuous current for radio purposes over the telephone line wires. This is the simplest form of control and the one nearest to present-day telephone practice, and is absolutely 65

certain not to produce any disturbance in adjacent conductors in the telephone cables. Each radiophone set is provided with a cut off relay energized when the telephone set goes into commission, either by calling or 70 being called, and at the central office whenever the radio operator takes control of the line, he disables it in the usual manner by pulling up the cut off relay at the telephone switchboard, this however being subject to 75 the condition that a special tone test may be put on, so that all operators may know that the line is held on the radio board, and subject to interruption for telephone connection. I prefer to use this tone test only 80 with the radio operator's testing plug, because his regular connecting plug includes within its functions that of connecting a subscriber through the station amplifier to the broadcasting transmitting set, and a connection of this character should not be interrupted without permission. 85

Referring now to the diagrams, Fig. 2, A and A' are two subscribers' stations connected by line wires 16—17 and 18—19 respectively to the central station C where they terminate on jacks J and J'. P—P' are plugs forming the terminals of a cord circuit 20—21, 22—23, having a bridged repeating coil I, ringing and listening keys K and 95 K', supervisory signals s—s' and bridging connection to the main battery B. The same battery is shown supplying current to the line relays L, L' and through contacts at the cut off relays L², L³ to the respective 100 lines for calling purposes. In this system, when a subscriber takes down his receiver, the line relay lights its lamp, which is extinguished when the operator inserts the answering plug. Battery supply for the connected lines is thereafter taken through the cord circuit 20—22, 21—23, in a manner well 105 understood in the art. When the substation telephones are out of service, with their receivers hanging on their hooks, the telephone 110 circuits are conductively open for direct current, leaving the ringers Q and Q' in circuit for alternating ringing current passing through the condensers q—q'.

Referring now to Fig. 3, it will be observed that the radio switchboard which I have designated generally by the letter R, is connected to the subscribers' lines by multiple taps marked 16^a, 17^a, and 17^b, and 18^a, 19^a, 19^b. These terminate on multiple jacks 115 J², J³, corresponding to the multiple jacks on the telephone switchboard. It should be noted that throughout this system the tip wires 16 and 18 with their branches are connected to ground, while the sleeve wires 17 and 19 and their branches, are connected to battery. This is extended into the radio 120 side of the system for the purpose of securing proper balance between the main battery or power plant of that side and the main 125 130

battery or power plant of the telephone side of the system.

At the subscribers' stations taps are also taken off from the telephone terminals to the radiophone terminals as indicated at 18^e, 19^e, and 19^d. (The radiophone is shown only at one substation for sake of simplicity of illustration). The two branches 19^e and 19^d are taken from the sleeve or battery side 10 of the line 19, and are connected to opposite terminals of the winding of a relay L⁴, which constitutes the substation cut off relay for the radiophone. The winding of this relay is bridged by a condenser q² through 15 which both ringing and voice currents can pass without substantial impedance. Where the radiophone is attached to a party line substation, this relay L⁴ may be omitted, since on such party lines there are usually 20 grounds on one side or the other. As will presently appear, the radio circuits described herein are applicable to two-party or four-party lines, with individual metering of the party stations.

25 Normally, that is to say, when the telephone circuit is not in use, the cut off relay L⁴ is deenergized and as a consequence the line wires 18^e and 19^e are connected through the back contacts of the relay through 30 switches 24 and 25 to the extreme terminals of the high impedance phantom coil 26, the middle terminal of which is connected through conductor 27 to the negative terminal of the "A" battery marked A² in Fig. 3, the plus terminal of which is grounded locally as shown. For completing the phantom charging circuit, the phantom coil 26 is matched by one side of the repeating coil of the operator's test cord circuit TC of Fig. 35 which coil has a central tap 170 to the negative terminal of the charging battery A³ the positive terminal of which is grounded locally.

40 The radiophone receiver at the substation A' is shown as comprising an antenna 28, tuned coupler 29, detector tube 30, audio amplifier tubes 31 and 32, and the usual transformers 33, 34, 35, the last mentioned transmitting the amplified audio waves to the telephone receiver or loud speaker 36. The filament battery is A². The plate battery is B¹ and suitable tuning condensers and coils, tickler coil for regenerative effects, etc., are provided as required. I 45 should remark in passing that this representation of the radio receiver is intended to be typical only. The present invention does not concern itself specifically with the design of the local radiophone sets, and other circuits and apparatus may be substituted for those shown in the diagrams without departure from the invention.

45 The pair of contacts 27^e, 27^d, close the wires 39 and 40, forming terminals of the secondary induction coil circuit I², to the

tip and sleeve side of the telephone line respectively, through the back contacts of relay L⁴. The transmitter T' is shown hanging upon a hook switch H' controlling the connection of wires 41 and 42, constituting a 70 parallel link between the battery A² and the filament bus 43. Thus the filament can be heated and the radiophone put in service. In addition to the hook, the subscriber has a manual switch h by which he can connect 75 the battery wire 42 through a wire 44 to his transmitter T', coil I' and ground, so as to energize his talking circuit. I provide an ordinary telephone receiver t' in series with the secondary of the induction coil I', 80 and I interpose a pair of condensers q³, q⁴ between the secondary of the induction coil I², and the receiver t' on the one hand, and the conductors 39 and 40 on the other, so that while the subscriber by means of switch 85 h can connect his phone T'-t' for receiving calls over the telephone line, he cannot originate calls thereover from the radiophone extension.

90 Returning now to the central station, and particularly to the radio department thereof shown in Fig. 3, T represents a broadcasting transmitter, symbolized in very simple form, but supposed to contain the usual elements of power supply, modulator, oscillator and aerial, with suitable amplification of the audio waves supplied on the input side. The jack J⁴ connected to the amplifier t² and thence to the transmitter T, symbolizes a group of such jacks or equivalent connecting means such as automatic switches, controlled by dials or keys for connecting any of the wire lines to said radio transmitter. Detailed appliances, both for the switching and for the radio transmission, 95 are well known in the art, and need no specific description in this specification, my present invention having to do particularly with the method of transmitting by wave radiation to the substations, and of bringing in all conversation originating or received at the substation radiophone over the subscriber's wire line. This includes repetition of modulated radio waves received at the radiophone substation and also originating messages gathered up and to be put through the amplifier t² on the transmitter T 100 for broadcasting.

105 It may be explained here that the transmitter T for general purposes is assumed to be the standard wave length transmitter for the local exchange area, to which all of the substations are tuned and upon which they depend both for original messages and programs and for those received and relayed from a distance.

110 The cord circuit between plugs P² and P³ in Fig. 3 is the same as the operator's cord circuit in Fig. 2, but the radio operator also has 115 special test cords such as that shown in the

upper part of the figure connected to plug P^4 . Here the keys $K-K'$ are of standard construction, as in the other cords, and the test contact of the plug P^4 is connected through suitable resistance to the supervisory lamp s^2 to the radio battery A^3 , means such as the commutator p^5 being provided to give special tone test on the test thimbles of the multiple jacks J^2, J^3 , etc. It will be noted that when this plug P^4 is inserted in a subscriber's radio jack J^3 , a phantom charging circuit is completed between the central office radio battery A^3 and the subscriber's radio "A" battery A^2 which circuit may be traced from the plus or grounded side of the battery A^3 through ground to the grounded plus terminal of the subscriber's battery A^2 , through A^2 to conductor 27, phantom coil 26, both sides of subscriber's line by way of contacts 24-25, contacts of relay L^4 , line branch conductors 19^a-18^a, into Fig. 2, line conductors 19-18, radio multiples 19^a-18^a into Fig. 3, through jack J^3 and plug J^4 and thence through windings 91 and 92 of the repeating coil 90, conductor 17 to minus terminal of battery A^3 . Two important advantages arising from this method of supplying current to the subscriber's radiophone set, are that the use of the line for the transmission of voice currents is not interfered with by the closure of the charging circuit, and that the current capacity of the line is doubled for the charging circuit.

The radio operator's testing and charging plug TC is also provided with a testing instrument in the form of a voltmeter V adapted to be connected through a switch S to the ringing key K in place of the ringing generator G , the circuit connections being such that one terminal of the voltmeter will be connected to both sides of the line while the other terminal of the voltmeter is grounded. Thus, as one terminal of the subscriber's A battery is connected to both sides of the line and the other terminal grounded, the voltmeter reading will indicate the condition of the subscriber's battery. It is to be understood that the voltmeter V is typical of any testing instrument which it may be desirable to use. The operator's listening set LS , which may be common to several cord circuits such as TC is provided with outgoing and incoming order trunks OG and IC , which lead to the listening set associated with the cord circuit C of the telephone operator, the trunk OG being normally opened or disconnected from the radio operator's listening set at the contacts OS , while the trunk IC is normally disconnected from the telephone operator's listening set at the contacts IS .

In operation, when the radio operator's plug TC is in a subscriber's jack, for example jack J^3 , the subscriber's battery A^2

will be charged from the central battery A^3 over the phantom circuit above described, and the cut-off relay L^3 (Fig. 2) at the telephone central switchboard will be held energized through the test contact 171 of the 70 cord circuit TC , which energizing circuit may be traced from the central office battery B , through supervisory lamp s^2 and its shunt through contact of supervisory relay 172 to test contact 171 and thence through test contact 172 of jack J^3 , test conductor 19^b into Fig. 2, cut-off relay L^3 to ground and back to the grounded side of the battery B . This disconnects the line signaling apparatus at the telephone switchboard to prevent false 80 signals due to the use of the line by the radio operator. Should the subscriber at A' desire to call the telephone operator for the purpose of establishing telephonic communication with another subscriber, while the line is held by the radio operator through the cord circuit TC , the subscriber rapidly opens and closes the tip side of his line by actuating the switch 25. Each time the tip side of the line is thus opened the 90 tip supervisory relay 172 is deenergized, opening the shunts around the supervisory lamp S^2 and causing the lamp to flash. This flashing of the lamp calls the operator using the cord circuit TC who, listening in by 95 means of the listening key K' and the listening set LS , may ascertain the wants of the subscriber and either pull the plug P^4 to give the subscriber control of the telephone switchboard line signal or close the contacts 100 OS and communicate over the outgoing order trunk OG with the telephone operator at the cord circuit C who will take the order and establish the connection. In emergency telephone connection can also be made 105 through cord TC direct. By closing the contacts 173, 27^c, 27^d, and switch h , the subscriber may converse from his radiophone set through the transmitter T' and telephone receiver t' . The energizing circuit 110 of the transmitter T' may be traced from battery A^2 through wire 42, and contacts of switch h , 44, T' , I' , and through ground back to battery A^2 , while the connection of the transmitter t' across the subscriber's 115 line may be traced from line wire 18, through line branch 18^e, contact of relay L^4 , contact 27^e, 40, g^3 , I^2 , t' , g^4 , 39, 27^d, contact of relay L^4 , line branch 19^e to line 120 wire 19.

Should the telephone operator desire to connect with the subscriber A' while the line cut-off relay is held up by the connection of the radio plug TC with the subscriber's radio multiple jack J^3 , the operator upon touching the ring or test contact of the multiple jack J' with the tip of the cord P' , instead of receiving the usual click in the receiver of her listening set, will receive a characteristic busy test due to the 130

- connection of the radio operator's busy test device P^5 with the multiple test wire 19^b . Upon receiving the characteristic busy test produced by the device P^5 the telephone operator will be apprised of the fact that the line is held busy only at the radio switchboard and may be connected with for its normal purpose of telephonic communication. Due to the high impedance of the phantom coil 26 to alternating current tending to pass through it across the line multiples 18^c-19^c , the operator may ring past the phantom coil through the ringing condenser q^2 . The subscriber A' upon raising his receiver from the switchhook in response to the call will bridge his transmitter circuit across the line in the usual manner which will close his line circuit through the cut-off relay L^4 which upon energization will open its contacts and disconnect the line extensions 18^c-19^c from the subscriber's radiophone set. Thus, during use of the telephone line for telephone purposes, from the subscriber's main telephone set, the radiophone set will be disconnected therefrom. As an alternative arrangement, contact L^{40} on the telephone switchhook, as shown in Fig. 2^a can be substituted for relay L^4 .
- When the radio operator is not connected with the subscriber's line through plug TC and the subscriber A wishes to establish connection with the radio operator, he signals the telephone operator by actuating the switch 174 to rapidly close and open the line which rapidly energizes and deenergizes his line relay L' and causes the line lamp l' to flash. This flashing of the line lamp instead of a steady lighting distinguishes the call for radio service from the usual call for telephone service so that the telephone operator may apprise the radio operator of the subscriber's wants over the order trunk IC without having to communicate with the calling subscriber.
- In Fig. 4 is shown an arrangement for supplying current over a grounded phantom on a magneto telephone line circuit to a radiophone receiver at the subscriber's station. In this instance the problem is simplified due to the absence of a line and a cut-off relay at the central office. In this arrangement RP represents the amplifier portion of the subscriber's radiophone which may be of any known or other suitable type having a pair of filament battery bus wires 175 and 176 connected respectively to the minus and plus terminals of a local "A" battery A^5 , the plus terminals being arranged to be out of connection with the wire 176 through switch 177 . The plus terminal of the battery A^5 is also connected to ground through one contact of the gang switch 178 while the minus terminal is connected through the other contact of the switch 178 and conductor 179 to the middle terminal of the phantom coil 180 bridged across the telephone line $181-182$. This coil is matched by a similar coil 183 similarly connected at the central office station C to the line and to the minus terminal of the battery A^6 the connection with the battery being made through conductor 184 , switch plug 185 , conductor 186 , charging bus 187 and choke coil 188 . The plus pole of the battery A^6 is grounded at the central station.
- When it is desired to charge the subscriber's battery A^5 , the gang switch 178 and the plug switch 185 are closed completing the phantom charging circuit which may be traced from the plus or grounded side of battery A^6 through ground to the subscriber's station, through contact of switch 178 , battery A^5 , conductor 189 , contact of switch 178 , conductor 179 to middle of coil 180 and thence over both sides of line $181-182$ through coil 183 , conductors 184 , 185 , 186 , 187 and 188 , back to battery A^6 . By operation of the switch 177 , the subscriber may connect his radiophone set in a local circuit with the battery A^5 independently of the condition of the charging circuit.
- In Fig. 5 I show an arrangement in which the idea of supplying battery to the radiophone subscribers is applied to private branch exchange systems, in which certain of the trunks T^5 , T^6 , T^7 , and T^8 leading from the main exchange M to the PBX station are phantomed with a charging circuit or circuits for storage batteries such as A^7 and B^5 which act as a common source of current supply for the radiophones RP^1 , RP^2 , etc., associated respectively with the private branch exchange, subscribers' telephone sets T^{10} , T^{11} , etc. The batteries A^7 and B^5 are the "A" and "B" batteries, respectively, for the subscribers' radiophone sets and are connected to the sets through the three bus wires 191 , 192 and 193 . These batteries A^7 and B^5 are arranged to be charged from the central office batteries A^8 and B^6 , respectively, over separate phantom circuits, or they may be alternately connected for charging to a single phantom circuit.
- A more detailed circuit diagram of the arrangement for charging the private branch exchange batteries each over a separate phantom circuit and from a separate central office charging battery, is shown in Fig. 6, where the two circuits are grounded phantom circuits imposed on the two trunks T^5 and T^6 leading from the main exchange M to the private branch exchange station PBX. As the trunk lines are identical, a description of one, T^5 will suffice. This consists of a pair of conductors $190-194$ terminating in the main exchange at the outside terminals of the winding 195 of a repeating

coil 196, and in the PBX station at the outside terminals of the winding 197 of a repeating coil 198. The winding 199 of the repeating coil 196 is connected through a 5 cut-off jack 200 to a drop signal 201 at the main telephone station, while at the PBX station the coil 202 is similarly connected to a cut-off jack 203 to the drop signal 204. To facilitate the passage of voice current 10 through the trunk from jack to jack, the repeating coils are bridged by telephone condensers 205 in the usual manner. At the main exchange the trunk side 195 of the repeating coil 196 is tapped at the middle and 15 connected through a conductor 206 and switch 207 to the plus terminal of the charging battery A⁸, the minus terminal of which battery is grounded at the main exchange. Similarly a conductor 208 connects the middle of the trunk side of the repeating coil 20 20 at the PBX station through a switch 209 to the plus terminal of the battery A⁷, the minus terminal of which battery is grounded at the PBX station. The trunk T⁶ and 25 its terminal apparatus is the same as the trunk T⁵ and has phantomed on it a charging circuit for the battery B⁵ which circuit is connected to the battery at the PBX station by way of the conductor 210 leading 30 through switch 211 and conductor 212 to the plus terminal of the battery B⁵ the minus terminal of which is grounded as shown. At the main station M the phantom circuit 35 is connected with the charging battery B⁶ by the conductor 213 which leads from the middle point of the trunk side of the repeating coil through the switch 214 to the plus side of the battery B⁶, the minus side of which is grounded. Thus, the batteries A⁷ 40 and B⁵ are connected to separate charging batteries A⁸ and B⁶, respectively, at the main station over separate grounded phantom circuits, one on the trunk T⁵ and one on the trunk T⁶. The primary sources A⁸ and 45 B⁶ at the main exchange are of sufficient voltage to affect proper charging of their respective secondary batteries A⁷ and B⁵. The common-battery supply busses 191, 192 and 50 193 are the same as those of Fig. 5, and so are multiplied to the battery consuming elements in the radio receivers. For example, where a detector tube or single tube set is used as indicated in Fig. 6, the filament and supply leads 216 and 217 are connected 55 to the busses 191—192, respectively, while the plate circuit conductor 218 is connected to the bus 193, the plate circuit return being effected through the filament lead 217 to the middle or common bus 192 as is usual where 60 a local set of batteries is used. To keep radio frequency currents off the busses 192 and 193 a radio frequency by-pass condenser 219 is connected as shown.

Where only one charging circuit is available the circuit arrangement of Fig. 7 may

be used in which is shown the single phantomed circuit imposed on the trunk T⁶ arranged to be switched in circuit with the battery A⁹ and generator A¹⁰, or the battery B⁷ and generator B⁸, according to which 70 battery is to be charged. In this arrangement the plate battery B⁷ is shown tapped at an intermediate point to supply detector voltage to the bus 193, while the fourth bus 220 is led from the extreme positive terminal for supplying plate voltage where 75 amplifier tubes are used.

Fig. 8 shows a further arrangement for 80 supplying current from the main station in which the primary energy is supplied over the trunk line T¹⁰ in the form of alternating current of superaudio frequency which may or may not be modulated with audio signals but which is transformed into the proper 85 form of energy for charging the secondary batteries A⁷ and B⁵ through a suitable high frequency motor 221 and a pair of generators 222 and 223 driven thereby.

In Fig. 9 is shown a further modification 90 of the idea of charging over a phantom circuit in which the batteries are charged by a pair of local generators 224 and 225 driven by a motor 226 supplied with power over the phantom circuit from a source 227 at 95 the main station.

I do not claim herein the arrangement of 100 bus circuits and supply from central, as shown in Fig. 5 nor the charging of batteries of the branch exchange to supply individual subscribers, nor the arrangement of generators and batteries shown in Figs. 7, 8, and 9, these features being claimed in my copending application, Serial No. 89,409, filed 105 February 19, 1926, as a division hereof.

What I claim is:

1. In a broadcasting system, a main station, a plurality of substations, means at 110 said main station for generating and transmitting to the substations radio waves, means at the substations for receiving said waves, metallic wire circuits from the main station to the substations, phantom circuits imposed upon said wire circuits, and a centralized source of current supply for the 115 substation receiving means, connected to said phantom circuits and distributed thereby to the several substations.

2. In a broadcasting system, a main station, a branch station, a plurality of wired 120 trunk lines from the main station to the branch station, a plurality of subscribers' substations, means at the main station for generating and transmitting radio waves, means at the substations for receiving said waves, individual wire circuits and common 125 multiple connections from the branch station to the substations, a phantom circuit imposed on one of said trunk circuits, and a centralized source of current supply for the substation receiving means distributed 130

to the several substations over said phantom circuit and said multiple connections.

3. In a broadcasting system, a main station, a branch station, a plurality of wired trunk lines from the main station to the branch station, a plurality of subscribers' substations, means at the main station for generating and transmitting radio waves, means at the substations for receiving said waves, individual wire circuits and common multiple connections from the branch station to the substations, a phantom circuit imposed on one of said trunk circuits, a storage battery at the branch station connected to the said common multiple connections for supplying current thereover to the several substation receiving means, and a centralized source of charging current connected with said storage battery over said phantom circuit.

4. In a broadcasting system, a main station, a branch station, a plurality of wired trunk lines from the main station to the branch station, a plurality of subscribers' stations, means at the main station for generating and transmitting radio waves, means at the substations for receiving said waves, individual wire circuits and common multiple connections from the branch station to the substations, a phantom circuit imposed on one of said trunk circuits, a storage battery at the branch station connected to the said common multiple connections for supplying current thereover to the several substation receiving means, and a centralized source of charging current connected with said storage battery over said phantom circuit, together with means associated with the substation receiving means for communicating with said branch and main stations over said individual wires and said trunks.

5. In a broadcasting system, a main station, a branch station, a plurality of wired trunk lines from the main station to the branch station, a plurality of subscribers' stations, means at the main station for generating and transmitting radio waves, means at the substations for receiving said waves, individual wire circuits and common multiple connections from the branch station to the substations, a phantom circuit imposed on one of said trunk circuits, a secondary source of current at the branch station connected to the said common multiple connections for supplying current thereover to the several substation receiving means, means at the branch station for charging said secondary source and a current source at said main station connected to said charging means over the phantom circuit.

6. In a combined telephone exchange and broadcast system, a main telephone exchange, subscribers' substations, means for generating and transmitting radio waves,

means at the substations for receiving said waves, individual line wire circuits from the main exchange to the substations, telephone link circuits at the main exchange for interconnecting said wire circuits for telephone purposes, a supervisory signal for each link circuit, a current supply circuit for the substation radio receiving means connected in a grounded phantom circuit imposed on the line circuit, grounded phantom current supply circuits arranged to be connected with one of the individual lines for supplying current to said substation current supply circuits over a grounded phantom circuit completed through the line upon connection of the supply circuit, a supervisory signal for each supply circuit, and means at the substations for selectively actuating said supervisory signals.

7. In a combined telephone exchange system and radio broadcast receiving system, a plurality of subscribers' substations, radio receiving means at said substations, individual wires connecting said substations with the telephone exchange station, connecting links at the telephone exchange station for interconnecting said line circuits for telephonic purposes, means for supplying current to the said substation receiving means over phantom circuits imposed on said individual wire circuits, link supervisory signals associated with said link circuits, supply supervisory signals associated with said phantom supply circuits, and means associated with said substation receiving means for selectively actuating said supervisory signals.

8. In a combined telephone and radiophone system comprising a plurality of telephone substations, a telephone central station, line wires interconnecting them, a plurality of radiophone substations, a radiophone central station, means to transmit messages from said radiophone central station to its substations by modulated high frequency waves, means at the radiophone substations to transmit messages telephonically, wire connections between the radiophone substations and telephone substations, wire connections between the radiophone central station and the telephone central station, phantom circuits connecting said radiophone central station with said substations superimposed upon said wire connections, supervisory signals at said telephone central station, supervisory signals at said radiophone central station, and means at said radiophone substations for actuating said supervisory signals at either said radiophone central station or telephone central station, selectively.

In testimony whereof I hereunto affix my signature.

EDWARD E. CLEMENT.
